UNITED STATES PATENT OFFICE.

STEPHEN S. THOMAS, OF WARREN, OHIO, ASSIGNOR TO THE ECOTHERMAL COMPANY,
OF WARREN, OHIO, A CORPORATION OF OHIO.

STOVE.

1,156,330.

Specification of Letters Patent. Patented Oct. 12, 1915.

Application filed August 29, 1912. Serial No. 717,741.

To all whom it may concern:

Be it known that I, STEPHEN S. THOMAS, a citizen of the United States, residing at Warren, in the county of Trumbull and State of Ohio, have invented certain new and useful Improvements in Stoves, of which the following is a specification.

The present invention relates to a new and improved construction of stove which 10 combines many of the desirable characteristics of a fireless cooker with others which are not possessed by the ordinary fireless cooker, but which are generally found in the usual stove or range.

15 In addition to all of the above advantages, the stove of the present invention possesses others which are not found in either of the previous constructions, but which are a result of the combining together of certain of 20 the characteristics of the fireless cooker with certain of those of the ordinary range.

The stove of the present invention is one which has its walls and doors so completely insulated against the passage of heat, that 25 after the desired temperature has once been established, it will be maintained with the application of a minimum amount of additional heat, and consequently with a maximum of efficiency.

30 The interior of the stove of the present invention is so arranged that the oven is completely protected against the entrance of any of the gases of combustion thereinto, and is so perfectly closed when the door is 35 shut as to entirely eliminate any drafts of air in or out. In addition, the passages for the movement of the hot gases are so disposed about the oven that the latter is uniformly heated on its sides, top and bottom, 40 so that there is little if any tendency for the air within the oven to circulate; in other words, the heat within the oven is a still heat and is practically unaccompanied by any air movement whatsoever.

45 I have so constructed the present stove that in obtaining the above results I may also make use of a broiler of extremely efficient design, the opening into which may be made entirely separate from that into the 50 oven, so that the latter need not be dis-

turbed when opening or closing the broiler, thus allowing the cooking processes to continue in the oven regardless of the broiler.

By reason of the high degree of heat insulation which is obtained in the herein described construction, it is found that after the oven and its contents have been brought to the desired temperature, the burner or other source of heat may be extinguished and the flues through which the gases enter 60 and escape may be closed, so that thereafter the heat will be retained in the oven and the cooking will proceed in a manner very similar to that of a fireless cooker. This 65 important difference is to be noted, however, that in the present case where the heat is initially introduced into the stove from a burner contained within the heat insulating enclosure, exactly the desired temperature 70 may be attained regardless of its intensity, whereas, in the ordinary fireless cooker, it 75 is sometimes very difficult to attain as high a temperature as desired, because the only heat contained within such cooker is that introduced through the medium of heated 80 bricks or the like, and other heated objects which may be placed within the cooker, and whose heat capacity is not definitely known. For example, it would be extremely difficult 85 if not impossible in the ordinary fireless cooker to attain a temperature high enough to carry on a roasting process, whereas such a process can be easily carried on in the stove of the present invention.

It was previously stated that after the desired temperature has been reached in the stove of the present invention, the flues may be closed, thus cutting off any further entrance or escape of gases, and retaining all 90 of the heat within the stove. In order to eliminate any danger of closing the flues while the burner is still open, and, on the other hand, to remove any danger of turning the gas on to the burner while the flues remain closed, I have provided an interlocking connection between the burner cock and the closure for the flues, by means of which 95 interlock, the aforementioned dangers are eliminated. It has been found by experience, however, that at times the closures for 100

the flues may be dispensed with, and that sometimes it is unnecessary to close the flues in order to retain a sufficient amount of heat within the stove.

5 The construction of the present invention is such that an extremely tight connection is provided when the oven door is closed. In fact, by means of the present construction, the oven may be closed so perfectly as 10 to retain within it any steam that may be generated by evaporation from liquids within the oven. Thus the temperature within the oven may be raised to a point considerably above the boiling point of water at 15 atmospheric pressure. In other words, by reason of the tight construction provided, temperatures considerably above the boiling point of water may be obtained within the oven, so that viands which would not ordinarily be thoroughly cooked at a temperature equal to the boiling point of water at 20 atmospheric pressure may be cooked in the oven of the present construction. Therefore, boiling processes may be carried on in 25 the oven at the same time that other foods are being roasted, and thus it follows that the necessary temperature may be attained for the roasting process, notwithstanding the presence of the vessels of boiling water. 30 Referring to the drawings, Figure 1 shows a front elevation of the completed stove with the oven door closed and the broiler door open; Fig. 2 is a cross section taken on line 2—2 of Fig. 3 looking in the 35 direction of the arrows; Fig. 3 is a longitudinal section taken on line 3—3 of Fig. 2 looking in the direction of the arrows; Fig. 4 is a horizontal section taken on line 4—4 of Fig. 3 looking in the direction of the 40 arrows; Fig. 5 is a horizontal section taken on line 5—5 of Fig. 3 looking in the direction of the arrows; Fig. 6 is a back perspective view of the front plate; and Fig. 7 is a 45 face view of the completed blank which is used for the back and top walls of the oven.

The numerals 10 and 11 designate the oven and broiler respectively.

A burner 12 placed immediately above the broiler directs its flame against a false bottom 13 secured to the bottom of the oven, the heated gases thence passing by way of side passages 14 and 15 to a top passage 16 above the oven. From the latter the gases flow downwardly at the rear of the oven 50 and broiler through the passage 17 to a point of exit 48 near the bottom of the stove.

A sheet 18 constitutes the backs of the oven and of the broiler, and has its upper 55 portion bent and extended forwardly to constitute the top of the oven. The extreme forward end 19 is flared out slightly for a purpose to be presently described. A U-shaped sheet 20 is secured to the back sheet in such 60 a way that in conjunction with the back

sheet it completely incloses the oven, with the exception of a front opening into which the door seats. The forward edge of the lower part of the sheet 20 terminates at the point 21, shown particularly in Fig. 3, while the sides thereof extend forwardly and are flared out at the points 22 and 23, as shown particularly in Fig. 4. A U-shaped sheet 24 has its rear edge secured to the back sheet, but is set at some distance below the bottom 75 of the oven to provide the spaces 25 and 26 between the broiler and the oven. The forward edges 27 of this U-shaped sheet 24 are also flared out, as shown particularly in Figs. 3 and 5, in a manner similar to the 80 forward edges of the sheet 20.

The back sheet 18, which also constitutes the top of the oven, is somewhat wider than the oven and broiler, so that its edges extend beyond the same to provide the passages 14 and 15. This fact is well illustrated in Fig. 4. Side plates 28 have their forward ends 29 bent inward and brought into contact with the side walls of the oven and rest against the edges of the sheet 18. 90 These side plates are of such a size to extend above the top of the oven and back of the plate 18 for the purpose of providing the passages 16 and 17 above and behind the oven. A sheet 30 lies parallel to the 95 sheet 18, both behind and above the oven, but has its forward end 31 bent down and into contact with the flared out portion 19 of the sheet 18. A bottom sheet 32 extends from the lower edge of the sheet 30 forwardly, and has its forward end 33 bent upwardly and flared out against the portion 27 of the bottom of the broiler.

The sheets thus far described, when set together, will provide a complete inclosure for 100 both the oven and the broiler, with the exception of their front portions. However, these are already partly inclosed by the upturned forward end of the bottom sheet 32, by the downturned forward end of the sheet 110 30, and by the inturned forward ends of the side sheets 28. Therefore, the parts thus far described serve to provide an inturned rim completely encircling the openings to both the oven and the broiler. 115

The construction thus far provided is surrounded by a layer of magnesia block or the like 34 which in turn is surrounded by a layer of suitable heat insulating material 35. Spacing angles 36 are placed along the edges 120 of the material 35 and serve to space a sheet metal inclosure a suitable distance from the material 35 to provide an air space 37. This sheet metal inclosure preferably comprises a U-shaped sheet 38 which constitutes 125 the bottom and side walls as is best shown in Fig. 2. A sheet 39 constitutes the top and a sheet 40 the back of the inclosure, all of said sheets being spaced by means of the angles 36, and by other devices when 130

necessary, the desired distance from the material 35. In order to give the inclosure a finished appearance, angle strips 41 are secured along the exposed edges, and corner pieces 42 are set onto the corners, all of said angles, corner pieces, etc., being held in place by screws 43 which extend through into the angle blocks 36. The latter thus perform two functions, namely, they space the outside sheets the proper distance from the material 35 to provide the air spaces and they serve as abutments into which the screws are threaded.

It is sometimes desired to provide flues or 15 the like through which the entering air and outgoing gases will flow. In the construction as herein illustrated these flues are placed in the back of the stove, and preferably in the air space 37, such air space being widened out if necessary to accommodate the flues. Assuming that the doors presently to be described have been closed, the incoming air will flow down through the right hand flue 44 and pass by way of a 20 connection 45 into the space 46 beneath the broiler. Thence it will pass upward at the sides of the broiler to the burner, whence the heated gases will pass up through the passages 14 and 15 at the sides of the oven 25 in the manner previously described.

It was previously stated that the gases would ultimately flow downward through the space 17 behind the oven and broiler to a point of exit. For this purpose an outlet flue 47 has its lower end tapped directly into the space 17 by a connection 48. With the above described construction, it is seen that both the inlet and outlet are in the upper portion of the rear of the stove. Both of 30 the flues 44 and 47 are open at their upper ends where they communicate with atmosphere. It was previously stated that at times it would be desirable to provide means for closing the flues for the purpose of cutting off any further circulation of air and for retaining the heat within the stove. For this purpose, a rod 49 extends across the upper portion of the rear air space and through the upper ends of the flues, it being provided with doors 50 and 51 for closing the flues themselves. This rod extends out to one side of the stove and terminates in a crank 52 which can be manipulated for controlling the doors.

55 For the purpose of providing a finish for the front portion of the stove and for providing abutments against which the oven and broiler doors will seat, I have provided the front piece shown in perspective in Fig. 6. The same comprises two vertical side plates 53 and 54 which are flush welded to top and bottom cross-plates 55 and 56 respectively. A central member 57 is formed somewhat in the shape of a tube so as to provide inner and outer walls 58 and 59 respec-

tively between which heat insulating material may be placed in manner similar to that in the remainder of the stove. This central member provides that portion of the inclosure between the oven and broiler doors. 70 It has its edges 60 and 61 seated against the upper and lower faces of the bottom of the oven and suitably secured to them, as is well shown in Fig. 3. The inner edges of the side plates 53 and 54 and of the cross-plates 55 and 56 are flared inward, so that they seat against the outwardly flared forward edges 22 and 23 of the oven and against the outwardly flared forward edges 80 of the broiler, as is well shown in Figs. 4 and 5, and against the outwardly flared forward edges 19 and 27 of the oven and broiler, as is well shown in Fig. 3. It will now be apparent that the member 57 taken in conjunction with the outwardly flared edges of the sides, top, and bottom will together provide surrounding abutments for the oven and broiler openings, and will serve to provide beveled faces against which the doors will tightly seat.

The oven and broiler doors are designated 62 and 63 respectively. They are of similar construction, and therefore a description of one of them will serve also for the other. The oven door constitutes a metallic pan 64 having its edges flared out and then turned flat down so as to seat flat against a plate 65, as shown particularly in Fig. 3. A gasket of sealing substance, such as rubber or the like 66 is placed around the inner face of the flattened out portion so that when the door is closed, this gasket will tightly seal the crack, and thus provide a practically air-tight joint. A channel member 67 completely surrounds the door and serves to hold the plate and pan together, as well as to hold the gasket against the pan. A bead of cast-iron or the like 68 surrounds the door and has its outer edge 69 extended downward so as to lie in the path of the channel 67 to prevent the same from coming loose.

A layer of magnesia block 70 and a layer of suitable heat insulating material 71 are placed within the pan and are held seated against its inside face by spacer blocks 72 so as to provide the air space 73. A ring of metal 74 provides an abutment into which screws 75 may be threaded for holding the bead in place.

Each door is suitably hinged at one side by hinges 76, as shown in Figs. 1, 4, and 5, and a lock 77 is provided at the other side of the door. The latter consists of a rotary cam block 78 having the handle 79 and working within a casing 80 of the door. The cam of this block engages an abutment 81 secured to a stationary portion of the oven. The firmness with which the door will be locked will depend simply upon the

pressure applied to the handle 79, so that the door can always be forced home to provide a practically air-tight seal.

It was previously stated that it was desired to secure such a distribution of heat about the oven as would give a practically uniform heating on all sides. Such a distribution of heat will largely if not entirely eliminate any tendency to the production of air currents within the oven, so that, as a consequence, practically a dead heat unaccompanied by air movements will be the result. With the construction thus far described, there might be a tendency for the upflowing gases to accumulate or draw together near the rear upper corners of the passages 14 and 15, and there might be a tendency for the downflowing air to rapidly draw together into the central part of the downwardly extending passage 17 and especially would this be the case at points close to the connection 48 which leads into the flue 47. In order to control the currents of gas so as to insure a practically uniform distribution, I have adopted an expedient of so proportioning the sizes of the passages themselves, or of so impeding the flow of gases through certain portions of the passages and facilitating the flow through other portions, that the resistance to the flow of gases in practically all paths will be the same, with the result that the distribution will be practically uniform.

It was previously shown that the sheet 35 18 which constitutes the rear of the oven and the broiler, and the top of the oven, was of full width extending entirely between the side sheets 28. Therefore the forwardly extending portion of this sheet 40 would cut off the side passages 14 and 15 from the top passage 16 unless openings or perforations were provided in it. To overcome this difficulty, I have provided perforations 82 best shown in Fig. 7 which 45 are arranged along the edges of the sheet 18. These openings are of different sizes depending upon their locations. In the construction illustrated, the forward ones are the largest and they range smaller in 50 size as they progress rearwardly. This is done for the reason that the gases passing up in the forward parts of the passages 14 and 15 must travel a longer distance than those passing up the rear portions of such 55 passages, and, therefore, in order to equalize the resistance of the several paths the sizes are proportioned somewhat as illustrated.

With the construction as thus far described, there might be a tendency for the gases to follow along the edges of the sheet 18 and thus to draw toward the sides of the upper passage 16 and of the downwardly extending passage 17. In order to overcome this tendency, I have provided a parti-

tion 83 best shown in Figs. 3 and 7 which partition extends entirely across the passage 16 and would, therefore, divide the same into two portions. I have, however, provided notches 84 in this partition, the sizes 70 of such notches being properly proportioned to secure the equal distribution of gases. In the construction illustrated, the largest notches are in the middle, and they range smaller as they progress sidewise. This is 75 for the reason that the longest paths for gas are those which extend down the middle of the passages 16 and 17.

I have adopted the partition construction illustrated for the purpose of insuring a tight 80 connection of the same against both of the sheets 18 and 30. The outstanding legs 85 of each partition may be welded or otherwise secured to the sheet 18 and the bend of the partition will then rest in contact with the sheet 85 30. In this manner when the stove is set together assurance may be had that the partition will efficiently serve the purpose for which it was intended. In the arrangement shown, the notches 84 are cut out of the 90 upper edge of the angle, although, of course, any other construction might be used.

The arrangements thus far adopted will give a fairly uniform distribution of heat, but there might still be a tendency for the 95 gases to draw together as they descended in the passage 17. In order to prevent this condition as much as possible, I have provided a second partition 86 across the lower portion of the passage 17, only a slight distance above the connection 48 which leads into the flue 47. This partition is likewise notched, but its notches are largest at the outside and range smaller as they extend inwardly. This is for the reason that the 105 longest paths for gas are those near the edges of the passage 17.

With the arrangements above described, a practically uniform distribution of gases is obtained, and an extremely uniform heating 110 of the oven is the result. I have, however, found it desirable to arrange two or more rows of perforations 88 across the bottom of the broiler for permitting a more uniform flow of air to the burner.

It was previously stated that where the doors were provided in the flues it would be desirable to interlock them with the burner cock, so that the doors could not be closed while the gas was applied, and so that, on the other hand, gas could not be applied until the doors were opened. For this purpose a spring 89 tends to rotate the shaft 49 and thus close the doors at all times. A link 90 extends down from the crank 52 to a bell crank 91 carried by a bracket 92 on the outside of the stove, a rod 93 extending forwardly from said bell crank and terminating in a button 94. By pushing backward on said button, the bell crank will be rotated 125 130

to draw the link 90 downward and thus open the doors against the force of the spring into the position shown in Fig. 3. The forward end of the rod 93 extends 5 through a bracket bearing 95.

The rod for controlling the burner valve is designated 96. On its forward end is provided a handle 97, by rotating which the gas is controlled. In the present instance, 10 I provide a disk 98 on the valve rod 96, said disk having a cutaway portion 99, so that when the valve is closed the button 94 will be projected past the disk and the doors closed by the action of the spring. Under 15 these circumstances, the gas could not again be applied until the user had pushed the button backward past the disk 98, to thereby again open the doors.

The preferred form of burner is that 20 illustrated. It comprises a U-shaped pipe 100, the gas from a supply pipe 101 being admitted to the central part of the U, as shown in Fig. 4. The branches of the burner are sawed to provide a number of 25 transverse slits from which the gas emerges, this construction being well known in the art. A bracket 102 secured to the false bottom provides a support for the inner ends of the burner so as to give a very rigid construction.

For purposes of heating water, I have provided a double reverse bend of water pipe 103, the water entering at the point 104 and leaving at the point 105. This heating coil 30 is located above the burner and has its bends offset to the sides thereof, so that the flame from each branch of the burner will strike two of the arms of the heating coil. This construction is well shown in Fig. 4, from 35 which it will be seen that an extremely efficient water heating system is thus provided.

When it is desired to attain an unusually high temperature in the oven, as much heat as possible should be conserved for heating 40 the gases. At such times, therefore, it would be desirable to reduce the amount of heat carried off by the water to a minimum.

For this purpose, I have provided a valve 45 106 which can never be completely closed, but will always leave at least a small passage, so that some circulation of water will take place at all times, and thus obviate the dangers of overheating the coil, or of generating steam.

50 In case it should be desired to allow steam and the like to escape from the oven as rapidly as it is generated, a connection 107 may be introduced into the oven, the same leading directly into the outlet flue 47. This 55 connection would not need to be large, as it would carry off the steam and the like as rapidly as generated.

It is preferred that the several sheets 60 should be electrically welded together, as by 65 this means a perfectly solid and uniform

connection may be established. Furthermore, by electric welding, it is very easy to obtain a perfect connection between one sheet and the edge of an abutting sheet. However, I do not in any wise limit myself 70 to any particular manner of establishing the connections.

I claim:

1. In a stove, the combination of an oven, a burner beneath the same, inclosures for 75 providing passages from the burner upward at the sides of the oven, other inclosures for providing passageways across the top of the oven and down behind the same, partitions in said passages for deflecting and 80 distributing the gases along a plurality of paths to obtain a uniform distribution of the gas currents, and an inclosure of heat insulating material surrounding the oven, burner, and passages, substantially as described.

2. In a stove, the combination of an oven, inclosures for providing passages upward at the sides of the oven, other inclosures for providing a passage across the top of the 90 oven and down behind the same, means for deflecting and distributing the flow of gases in the passages along a plurality of paths for the purpose of effecting a uniform distribution of the gases, and means for initially heating the gases, substantially as described.

3. In a stove, the combination of an oven, inclosures for providing passages upward at the sides of the same, other inclosures for 100 providing a passage across the top of the oven and down behind the same, partitions between the side passages and the top passage, there being perforations in said partitions of sizes varying accordingly to the 105 lengths of the gas paths, partitions in the top and back passages, there being openings in said partitions varying in size according to the lengths of the gas paths, whereby the resistances of all the gas paths are substantially the same, and means for initially heating the gases, substantially as described.

4. In a stove, the combination of an oven, inclosures for providing passages upward at the sides of the same, other inclosures for 115 providing passages across the top of the oven and down behind the same, a burner beneath the oven, an inclosure of heat insulating material incasing the oven, burner, and passages, a cover surrounding the inclosure 120 of heat insulating material and spaced therefrom a desired distance in its back side to provide an air space, a pair of flues located in said air space behind the downwardly extending passage, a connection from one of 125 said flues to the lower ends of the upwardly extending passages, and a connection from the other flue to the lower end of the downwardly extending passage, substantially as described.

5. In a stove the combination of an oven, inlet and outlet gas connections, passages adjacent the walls, back, and top of the oven for the flow of gas from the inlet connection to the outlet connection, a heater located at a convenient point adjacent to the inlet connection, and means for distributing and directing the gases along a plurality of paths adjacent to each of the surfaces of the oven,
10 whereby the gases flowing adjacent each sur-

face of the oven maintain the same general direction of movement and whereby a substantially uniform distribution of heat in the oven is obtained, substantially as described.
